United States Patent Office.

A. J. ROBINSON, OF TROY, NEW YORK.

Letters Patent No. 60,790, dated January 1, 1867.

IMPROVED MOP-WRINGER.

The Schedule referred to in these Letters Patent and making part of the same.

TO ALL WHOM IT MAY CONCERN:

Be it known that I, A. J. ROBINSON, of Troy, in the county of Rensselaer, and State of New York, have invented a new and useful improvement in Mop-Wringer; and I do hereby declare that the following is a full, clear, and exact description thereof, which will enable others skilled in the art to make and use the same, reference being had to the accompanying drawings, forming part of this specification, in which—

Figure 1 is a top view of a portion of a tub or pail with my improved mop-wringer attached.

Figure 2 is a side view of the same.

Figure 3 is a top view of the bar by means of which the wringer is attached to the tub or pail.

Figure 4 is an edge view of the same.

Similar letters of reference indicate like parts.

My invention has for its object to furnish an improved means by which a mop may be wrung without its being necessary to take hold of it with the hands for that purpose; and it consists of a mop-wringer and supporting bar, constructed as hereinafter more fully described.

A is the tub or pail, to the inner side of which the bar, B, of the mop-wringer, C, is attached. The bar B is formed with its ends curved to correspond with the curve of the side of the tub or pail to which it is to be attached. These curved ends have upwardly projecting flanges, b¹, having holes made through them for the passage of the screws by which the said bar is secured to the side of the tub or pail, A, as shown in fig. 2. The central part of the bar B is made thicker, or has a projection, b², formed upon it, to strengthen it where it is weakened by the slot for the reception of the tenon c¹ of the wringer C. The upper part of the wringer C is in the form of a circle, with the central part cut away; and from the circular rim, e², thus formed, two arms, e³, descend spirally to the lower part, e⁴, as shown in figs. 1 and 2. These spirals, e³, should make at least one entire revolution in their passage from the upper part or rim, e², to the lower or central part, e⁴. The drawing represents the wringer as being formed with two spiral arms, e³, but more than two may be used, if desired, and when the wringer is made large this may be desirable. Upon the lower side of the central or lower part, e⁴, is formed a tenon c¹, which fits into the slot formed in the middle part of the bar B, as shown in fig. 2. The tenon c¹, lower part c⁴, spirals e³, and rim c², may all be formed solid in one piece, if desired. In using the wringer, the lower end of the wet mop is placed in the cone-shaped central cavity formed by the spirals, and turned about in the direction in which the spirals run from the rim c² to the lower part e⁴. The effect of the spiral arms e³ is to draw the mop downward, compressing it into the gradually decreasing cavity and squeezing out the water quickly and thoroughly without its being necessary to take hold of the mop with the hands.

What I claim as new, and desire to secure by Letters Patent, is—

An improved mop-wringer, formed by the combination of the bar B and wringer C, constructed with a circular rim c², two or more descending spiral arms e³, lower central part c⁴, and tenon c¹, substantially as herein described and for the purpose set forth.
